UNITED STATES PATENT OFFICE.

SAMUEL G. GOSS, OF GLENCOE, ILLINOIS, ASSIGNOR TO THE GOSS PRINTING PRESS COMPANY, OF CHICAGO, ILLINOIS, A CORPORATION OF ILLINOIS.

BINDING AND FOLDING MACHINE FOR PRINTING-PRESSES.

988,567.

Specification of Letters Patent.

Patented Apr. 4, 1911.

Application filed June 10, 1910. Serial No. 566,151.

To all whom it may concern:

Be it known that I, SAMUEL G. Goss, a citizen of the United States, residing at Glencoe, in the county of Cook and State of Illinois, have invented certain new and useful Improvements Relating to Binding and Folding Machines for Printing-Presses, of which the following is a specification, reference being had to the accompanying drawings.

My invention relates to binding and folding machines for printing presses and its object is to produce a new and improved form of machine in which a plurality of superposed sheets are brought into proper position and registry with each other, are then stitched together and forwarded into folding mechanism to be folded.

More particularly still my invention relates to a new and improved form of such machine in which superposed sheets, brought into registry, are engaged by a traveling stitching mechanism, which, while stitching the sheets together by its movement, forwards the sheets into folding mechanism.

It has for a further object improvements in machines of this character hereinafter specified more particularly in detail.

In the accompanying drawings:—Figure 1 is a top or plan view; Fig. 2 is a side view seen from the gearing side of Fig. 1; and Fig. 3 is an end view viewed from the delivery end of the machine shown in Fig. 1.

Referring to the drawings,—4 indicates the framework of a folding and stitching machine upon which the parts hereinafter described are mounted.

5 indicates a table mounted in the framework of the machine and provided with registering guides 6—7 by means of which the sheets are brought into proper registry when fed in to the table 5, as hereinafter described.

8 indicates tapes which pass around rollers 9 on shaft 10.

45 11 indicates tapes which lead into the machine around roller 12. Tapes 8 stop short of the table 5 while tapes 11 pass across and beyond it. The rollers 12 are journaled upon shaft 13 which is supported upon arms 50 14—15. The arms 14 are mounted by hubs or collars 16, integral with said arms, upon rock-shaft 17 which is journaled upon brackets 18 supported on the framework 4. The arm 15 is also provided with a suitable 55 collar 19 by means of which it is secured

to the rock-shaft 17. The collar 19 is provided with a rock-arm 20 preferably integral therewith.

21 indicates a connecting-rod which is pivotally connected at its upper end to rock-arm 20. The lower end of the connecting-rod 21 is provided with a fork 22 which straddles the shaft 23.

24 indicates a roller which is carried on the lower end of the connecting-rod 21 and is adapted to bear against the cam 25 secured to shaft 23. The shaft 23 is rotated by beveled gears 51—52 suitably connected with the driving gear of the machine, and driven therefrom. The roller 24 is kept in constant contact with the surface of the cam 25 by spring 28. As the shaft 23 rotates and rocks the cam with it the high part of the cam will throw the rock-arm 20 upward, the arm 15 downward, lowering rollers 12 and with them tapes 11. When the roller 24 is upon the low part of the cam the rollers 12 will be correspondingly lifted lifting the tapes 11 for purposes hereinafter set forth.

30 30 indicates tapes which pass into the machine over roller 31 and around roller 32. The tapes 30 are located below and in registry with tapes 11, and, moving in the direction shown by the arrow in Fig. 3, will operate to feed sheets into the machine. 35 The tapes 8, 11 and 30 are shown broken away. They lead from any suitable sheet-gathering mechanism, not shown, and the gathered sheets, brought into the bite of the tapes in any well known manner, are carried 40 by the tapes 8, 11 and 30 into the machine upon the table and are brought into registry, for stitching, by the registering bars or guides 6—7 upon the table.

It will, of course, be understood that the 45 gathered sheets may all come from one gathering mechanism or from several mechanisms such, for instance, as a number of sheets gathered together from one mechanism and a cover from another mechanism 50 and an insert sheet or sheets from another mechanism. As such mechanisms are known in the art, and as the gathered sheets are fed into the tapes by any well known mechanism, such gathering mechanism and mechanism for feeding the sheets into the bite of the tapes are not shown or described in order not to unduly complicate the drawings.

55 35 indicates a bed-plate mounted on and secured to the framework 4. 110

- 36 indicates a carriage which consists of a base 37 and brackets 38 having arms 39 and 40. The arms 39 and 40 extend inwardly over the table respectively above and below it. The base 37 is slidingly mounted upon bed-plate 35, between guide bars 41, so as to reciprocate back and forth upon the bed-plate 35, carrying with it, of course, brackets 38.
- 10 42 indicates a rock-shaft journaled in brackets 43, on the frame of the machine, and provided with arm 44 and arms 45. The arms 45 are connected by links 46 with suitable lugs, as 47, preferably formed integrally with the base 37. The arm 44 is connected by an adjustable link-rod 48 with an eccentric 49, secured to shaft 50 which is driven by suitable gearing not shown, on the opposite end of the shaft from bevel gears 20 51—52 and connected in any suitable manner with the driving gearing of the machine. The rotation of shaft 50 and eccentric 49, of course, operates to rock the rock-shaft 42 and reciprocate the base 37 back and forth 25 on the bed-plate 35, carrying arms 39 and 40 back and forth across the table 5 in a direction at right angles to that in which the sheets are fed to the table by the tape as above described.
- 30 53 indicates staplers which are mounted upon the inner ends of arms 39 and coöperate with anvils 54, upon the inner ends of arms 50, to stitch the sheets together, on table 5, by wire staples. This stitching mechanism and the anvils may be of any 35 approved form and construction and are actuated in any well known and approved way. As such stitching mechanisms are well known I have not illustrated and do 40 not describe the same in order not to unnecessarily encumber the drawings and description. It is sufficient to say that by any well-known actuating means the stitchers are at proper intervals lowered upon the sheets so 45 as to engage the sheets between the stitching mechanism and the anvils and staple the sheets.
- 55 indicates a folding cylinder, which is provided with grippers 56 and is in the form 50 in which my present invention is embodied, of a circumference equal to substantially one sheet length.
- 57 indicates folding-knives which are carried by cylinder 55. The grippers are actuated to close upon the lead edge of the sheet and release the same at proper intervals in any well-known manner, not shown, and the folding-blade 57 is actuated in any well-known manner, not shown, in order not to 60 unnecessarily complicate the drawings.
- 58 indicates rollers carried by brackets 59 and geared to the driving-gear of the folding cylinder. The rollers 58 are cut away slightly around most of their periphery so 65 as to not be in contact at such cut-away por-
- tion with the surface of cylinder 55, but are provided at a portion of their periphery with a longitudinal bearing strip 60 which is adapted, as the rollers rotate, to come into sufficiently close contact to press the pile of 70 sheets against the cylinder 55. The surfaces of strips 60 of the rollers 58, of course, travel at the same surface speed as the cylinder 55 and are of a radius whose described circle is one-third the circumference of the folding 75 cylinder 55 so that they engage the paper between them and cylinder 55 at the lead margins of the sheet, the center of the sheet and tail margin of the sheet.
- 61—62 indicate folding-rollers, of any 80 well known form and description, journaled in the framework 4. The lower roller 61 is driven by gear 63 geared to one of the driving-gears 64 of the machine. The roller 62 is journaled in the hubs 65 on rods 66 85 spring-seated in bearings 67, in the well known way, so as to coöperate with roller 61 in forwarding the paper when it is tucked between them, in the usual way, by folding-blade 57.
- 89 68 indicates guides mounted on the framework of the machine. The folding-rollers 61—62 direct the lead end of the folded sheets against the guide 68 down which they travel to be taken by the usual S-fly 69 and 95 delivered thus to slow moving tapes 70. The guide 68, S-fly 69 and slow tapes 70 are well-known in the art and need no further description.
- 90 The operation of the above device is as 100 follows:—The superposed sheets coming, from any suitable accumulating or gathering mechanism or mechanisms, into the bite of the tapes 8, 11 and 30 are fed forward to table 5 and put into registry thereon by 105 guides or registering stops 6—7, the stops being so adjusted that the central line of the sheet, longitudinally of its first path of travel, on which the sheets are subsequently folded, is in registry with the stitchers 55. 110 At this moment the stitchers 55, operated by any well known actuated mechanism, close upon the sheets and staple the same. At the same time, and as soon as the stapling begins, the parts are so adjusted that the 115 forwarding movement of the carriage 36 begins, that is to say, it begins to travel toward the folding cylinder 55—namely to the right in Fig. 2. This forwarding motion of the stitchers, the table, of course, being 120 suitably slotted as at 80 for the purpose, moves the pile of sheets to the right in Fig. 2, that is, toward the delivery cylinder 55, in position to be engaged by the grippers 56. The staplers then separate and the 125 movement of the carriage in the opposite direction begins to bring them into position for another operation. At the same time that the stitching and forwarding motion of the stitchers begins the roller 24 drops 130

to the low part of cam 25 and the roller 12, lifted thereby as above described, lifts tapes 11 enough to free the sheets from the tapes and not interfere with the forwarding motion. The grippers 56 operate, in any well known way, to seize the lead edge of the sheet. At the same time the bearing-strips 60 on rollers 58 come into position to press the sheet, immediately behind the grippers, upon the surface of the cylinder 55 so as to insure the bite of the grippers.

The pile of sheets, carried around the cylinder by the grippers, are folded in the well-known way by the folding-blade 57 upon their center line of stitches between folding-rollers 61-62 and delivered therefrom by means of guide 68 and S-fly 69 to moving tapes 70. As soon as the pile of sheets is clear of the table the cam 25 operates to lower rollers 12 and tapes 11 to again forward the next oncoming pile of associated sheets to the table as before.

What I claim as my invention, and desire to secure by Letters Patent, is,—

1. A stitching and folding machine, including in combination, means for forwarding a plurality of associated sheets, means for stopping the same in registry, a folding mechanism, a reciprocating carriage, means for reciprocating the same, and stitching mechanism carried by said carriage and adapted to stitch the registered sheets and adapted by the movement of said carriage to forward the sheets while being stitched to said folding mechanism.

2. In a combination, a table, means for forwarding a plurality of associated sheets to said table and stopping them in registry thereon, folding mechanism, a traveling support, and stitching mechanism carried by said traveling support and adapted by the movement of said support toward said folding mechanism to move the stitched sheets into engagement therewith.

3. A binding and folding mechanism, including in combination, means for conveying a plurality of associated sheets along a straight path, means for stopping said sheets in registry, folding mechanism located at one side of said path, a reciprocating carriage, means for reciprocating the same, and stitching mechanism carried by said carriage in the line of said path and adapted to stitch said registered sheets and by the forward movement of said carriage to forward the same to said folding mechanism.

4. A binding and folding machine including in combination a plurality of reciprocating stitchers, means for feeding sheets into position to be stitched by said stitchers, and folding means adapted to engage said sheets when thus forwarded by said reciprocating stitchers and fold the same.

5. A binding and folding machine including in combination a plurality of recipro-

cating stitchers, means for simultaneously stitching and moving away the sheets, and folding means adapted to engage said sheets when thus forwarded and fold the same.

6. A binding and folding machine including in combination a carrier having gripper mechanism, moving stitchers, means for stitching the sheets while the stitchers are in motion, means for moving the sheets into engagement with said gripper mechanism while being stitched, and folding means adapted to engage said sheets when thus forwarded and fold the same.

7. A binding and folding machine including in combination a carrier having gripper mechanism, a reciprocating carriage, means for reciprocating said carriage toward and away from said carrier, stitchers mounted on said carriage and adapted to stitch a plurality of registered sheets while said carriage is reciprocating toward said gripper mechanism, and thereby to bring said sheets into position to be engaged by said gripper mechanism, and folding means adapted to fold said sheets off said carrier.

8. A binding and folding mechanism, including in combination, means for conveying a plurality of associated sheets along a straight path, means for stopping said sheets in registry, folding mechanism located at one side of said path, a reciprocating carriage, means for reciprocating said carriage at right angles to the path of travel of said sheets, and stitching mechanism carried by said carriage and adapted to stitch said sheets along the line of their travel and, by the movement of said carriage toward said folding mechanism, to forward said sheets into engagement therewith.

9. A binding and folding mechanism, including in combination, a table, means for forwarding a plurality of associated sheets to said table, means for stopping them in registry thereon, a folding cylinder, folding rollers in operative relation therewith, a reciprocating carriage, and stitchers mounted on said carriage and adapted to stitch said registered sheets and by the reciprocation of said carriage to forward said sheets to said folding cylinder.

10. A binding and folding mechanism, including in combination, a table, means for forwarding a plurality of associated sheets to said table, means for stopping them in registry thereon, a folding cylinder, gripping mechanism on said folding cylinder and adapted to engage the lead end of a pile of sheets when forwarded thereto, a roller in coöperative relation with said folding roller and having a bearing surface adapted to engage the lead ends of the sheets immediately behind the grippers, folding rollers in coöperative relation with said folding cylinder, a reciprocating carriage, and stitchers mounted on said carriage and adapted to

stitch said registered sheets and by the reciprocation of said carriage to forward said sheets to said folding cylinder.

11. A binding and folding mechanism, including in combination, a table, means for forwarding a plurality of associated sheets to said table, means for stopping them in registry thereon, a folding cylinder, gripping mechanism on said folding cylinder and adapted to engage the lead end of a pile of sheets when forwarded thereto, a roller in coöperative relation with said folding roller and having a longitudinal bearing strip adapted to engage the lead ends of the sheets immediately behind the grippers and also to engage the center line of the sheets transverse of their then path of travel between it and said cylinder, folding rollers in coöperative relation with said folding cylinder, a reciprocating carriage, and stitchers mounted on said carriage and adapted to stitch said registered sheets and by the reciprocation of said carriage to forward said sheets while being stitched to said folding cylinder.

12. A stitching and folding machine, having in combination, a table, means for forwarding a plurality of associated sheets along the straight path to said table, means for stopping said sheets in registry on said table, a folding cylinder located at one side of said table, folding rollers in coöperative relation therewith, a carriage, means for reciprocating said carriage in a direction toward and away from said folding cylinder, and stitching mechanism carried by said carriage and adapted to stitch said regis-

tered sheets and by the movement of said carriage toward said folding cylinder to forward the same while being stitched to said folding cylinder.

13. In a binding and folding machine, in combination, means for forwarding a plurality of sheets, a carriage, a plurality of stitchers adapted to stitch said sheets, grippers adapted to engage the lead edge of said stitched sheets, and means for operating said carriage to forward said sheets while being stitched to said grippers.

14. A binding and folding machine including in combination a plurality of stitchers, means for forwarding said sheets into position to be stitched by said stitchers, means for registering said sheets for stitching, means for moving away said sheets in a direction transverse to the direction of their feeding in to said stitchers and on the same horizontal plane, and folding devices adapted to grip the edge of said stitched sheets as they are moved in said transverse direction and fold the same.

15. A binding and folding machine, including in combination, a plurality of stitchers, means for feeding sheets into position to be stitched by said stitchers, means for moving away the sheets while being stitched, and folding means adapted to engage said sheets when thus forwarded and fold the same.

SAMUEL G. GOSS.
